G. H. NOBBS.
INTERNAL COMBUSTION ENGINE.
APPLICATION FILED NOV. 22, 1919.

Patented June 6, 1922.

UNITED STATES PATENT OFFICE.

GEORGE H. NOBBS, OF WATERTOWN, MASSACHUSETTS.

INTERNAL-COMBUSTION ENGINE.

1,418,668.

Specification of Letters Patent. Patented June 6, 1922.

Application filed November 22, 1919. Serial No. 339,786.

To all whom it may concern:

Be it known that I, GEORGE H. NOBBS, a citizen of the United States, residing at Watertown, in the county of Middlesex and 5 State of Massachusetts, have invented certain new and useful Improvements in Internal-Combustion Engines, of which the following is a specification.

This invention relates to improvements 10 in internal combustion engines. More particularly it relates to two stroke cycle engines, and, therein, to the deflector on the top of the piston and to means for balancing the eccentricity of the crank pin.

15 The invention is illustrated as it may be applied to a small engine suitable for use in portable machinery, having been developed by me in connection with a small tractor wherein it was desirable to provide 20 the required power with a relatively small weight of engine; but it appears that the invention can be applied advantageously to engines otherwise constructed, used for any 25 of a wide variety of purposes, the general effect of applying the improvement to an existing design of engine being to give ease 30 of starting, steadiness and certainty of operation, and a high degree of perfection of combustion, qualities which always have been difficult to attain, and often have been 35 grievously lacking, in small engines heretofore made, of which engines used in small boats are an example. In addition, it is observed that more power is obtained from 40 a given engine by the use of the invention therewith. The improvements in question comprise making the deflector, which extends as a chord across the top of the piston, extend to the very periphery of the 45 cylinder so that its end faces approximately bear against the cylinder walls, thereby preventing passage of gas between the end of the deflector and the cylinder wall; and comprises the making of the necessary balance 50 for the crank pin by cutting a segment away from the balance wheels. The cutting is on the same side of the axis with the crank pin and is symmetrical with respect to an extension of the medial plane of

55 of exterior form of the wheels, as distinguished, for example, from the mere elimination of an equal amount of material by borings therein. It seems probable that the improved results noted follow from the change in shape of the containing chamber which occurs, in such a construction as 60 a result of the rotation of the segmental space, between the time of intake of charge into the crank chamber and adjacent part of the cylinder, and its transfer thence into the 65 working part of the cylinder. As developed by me, it has been applied to an engine of the three-port type, but it appears that it may be otherwise applied, and that embodiments of the invention may 70 vary in sundry particulars. It is intended that the patent shall cover, by suitable expression in the appended claims, whatever features of patentable novelty exist in the invention disclosed. 75

In the accompanying drawings, which illustrate an embodiment of the invention,

Figure 1 is a side elevation in medial section through the cylinder, piston and shaft of a two stroke engine; 80

Figure 2 is a similar medial section, looking endwise of the shaft;

Figure 3 is a detail of the piston in perspective; and

Figure 4 is a detail of one of the fly 85 wheels seen in the same direction as in Figure 2.

Referring to the drawings, 10 indicates a cylinder having a piston 11, a piston rod 12, and a crank 13 on a shaft 14. The cylinder has an intake port 15, below the piston, admitting a charge to the crank case; a passage 16 arranged to co-operate with an admission port 17 in the piston for letting a charge that has been compressed in the 90 crank case be transferred into the cylinder; has on the piston a deflector 18, by which the charge admitted to the cylinder is directed upward; and has an exhaust port 19, all of which parts are arranged in any ordinary or suitable way, except for the special features associated with the deflector about 95 to be described. The engine also has a crank case 20 communicating with the open end of the cylinder, within which case are 100 two fly wheels 21, one on each side of the crank, fitting and substantially filling the portion of the crank case where they are,

except such parts of it as are needed clear for motion of the crank and piston, and except that the normal circular shape of the wheels is deformed by the removal of a segment leaving a flat side 22. The space thus left by the removal or absence of metal from the perfect circular form of the fly wheels is symmetrically located with respect to the radius which passes through the crank pin, 5 and is sufficient in size to afford a balance for the weight which is eccentrically disposed in the crank pin and its associated parts. It is, therefore, on that side of the fly wheels which is toward the piston when 10 the piston is at inner dead center, as illustrated in Figure 2. The removal of sufficient material to effect the desired balance is also sufficient to leave an open space of substantial extent within the solid of revolution described by the fly wheels. Said 15 solid of revolution fits the crank case closely, and as the metal of the wheels substantially fills it, and thus fills that portion of the crank case, except as is requisite for movement of the connecting rod, the space for 20 containing the charge is mostly concentrated in a body above. When the piston is at the inner end of stroke, as illustrated, the open space left by the absence of material from 25 the fly wheels is continuous with the main body of charge-holding space enclosed by the lower portion of the cylinder and the upper portion of the crank case. The intake port 15 is open, while the piston is approaching the said position, and is closed 30 by a check valve, not shown in the drawings, during recession therefrom, as is common practice. During all of this time, the 35 said space contains substantially all of the air and gas which are to constitute the next charge. With an engine built in the proportions indicated in the drawing, there is about a third of a revolution from where the segment begins to connect with the said 40 main space, to where it ceases, as shown by the interval between initial and final positions of the chord 22 indicated by dash lines 22' and 22''. During this interval, the flat surface 22 is sweeping around, changing its 45 angle through nearly a complete reversal, and at the same time is rapidly shifting the shape of the lower end of the main space; and this occurs at a time when the piston and upper end of the piston rod are relatively 50 stationary. It is my opinion that the sweep of the chord 22 past the axis of the piston, with the resulting change of shape of the lower part of this main space, and deflection of gases therein, produces such a 55 fanning and agitation of gaseous contents reaching up into the upper part of the space in its effects that the mixture of air and gas therein is perfected, thus producing improvement in the operation of the engine. 60 In particular, the engine on which compar-

ative experiments have been made is observed to get its initial ignition or "starting" more easily, to deliver greater power, and in general to run more steadily and with more perfect combustion. 70

Another feature contributing to these improved results is the arrangement of the deflector. This is best illustrated in Figure 3, where the end portion 23 of the deflector is clearly represented as being a cylindrical 75 surface continuous with and of equal curvature with the cylindrical surface of the piston, which, of course, is approximately of the same radius of curvature as is the cylinder wall. The advantage of this feature 80 is that whereas hitherto it has been the practice to make the deflector a simple ridge upstanding from the top of the piston and not reaching to the cylinder wall, I have discovered that a saving is effected by the 85 construction described. I believe the reason to be that at the time of transfer of charge into the part of the cylinder above the piston there is in progress a considerable rush of products of combustion out 90 through the exhaust port, and that some of the incoming charge is drawn out with the products of combustion, passing between the ends of the deflector as heretofore constructed and the adjacent walls of the cylinder without being deflected upward into the top part of the cylinder according to the purpose for which the deflector is installed. This loss is prevented by the construction 95 now disclosed, in which the end of the deflector fits the cylinder wall, and the entire 100 entering charge is projected with momentum upward.

Details of construction of the engine may be greatly varied. In the engine illustrated, 105 the crank pin 13 is made integral with the two parallel crank arms 24 which are set into recesses in the two fly wheels 21; and the whole is held together by a single bolt 25 which passes through an axial hole in 110 the crank pin and so clamps together the two fly wheels 21, with the two arms 24 set in their respective recesses 24' so that the fly wheels have to rotate with the arms and therefore with the crank pin. The fly wheels 115 are further held together, by the bushings in the crank case, where the main shaft passes through it. This makes an extremely simple construction, in which the compactness and security of fastening, and the in- 120 expensiveness of labor and machine costs in manufacture are features of advantage.

I claim as my invention:—

1. The combination, in an internal combustion engine, of a cylinder and a crank case arranged to receive a mixture of fuel and air, and a balance fly wheel rotatable within the crank case, having its sides and face closely fitting the walls thereof except that said wheel is deformed from circular 125 130

shape on a part of its face which rotates past the cylinder end between the time of intake and discharge of said mixture.

2. The combination, in an internal combustion engine, of a cylinder and a crank case arranged to receive a mixture of fuel and air; a crank in said case; and a pair of balance wheels, attached to the crank therein on its opposite sides and rotatable therewith; each of said wheels fitting within and approximately filling the case on its side of the crank, except that its face is deformed from circular shape, so as to agitate the said mixture during its rotation.

15 3. The combination, in an internal combustion engine, of a cylinder and a crank case arranged to receive a mixture of fuel and air; a crank in said case; and a pair of balance wheels attached to the crank therein 20 on its opposite sides and rotatable therewith; the said flywheels approximately filling the space in the case around the crank shaft and beside the crank, and being set with the path of revolution of their faces 25 close to the lower limit of piston travel; there being a weight-balancing and mixture-agitating deformity from circular shape on the face of each wheel, on the same side of the axis with the crank.

30 4. The combination, in an internal combustion engine, of a cylinder and a crank case adapted to receive a mixture of fuel and air, a crank in said case and a flywheel attached thereto with its face closely fitting 35 the circular wall of the case except where the wheel is minus a segment cut off by a chord extending across the side of the wheel outside of its connection with said crank; said cut off portion of the face being so

arranged as to pass the cylinder end during 40 the time when the capacity of said end is changing slowly.

5. The combination, in an internal combustion engine, of a crank case, a crank shaft and crank therein, and a pair of fly 45 wheels mounted on said shaft and attached to said crank and approximately filling the space in the crank case around the shaft and crank, except for the space in which the connecting rod moves; the crank comprising 50 a hollow crank pin and two arms rigid therewith extending perpendicular to the shaft between and recessed in the fly wheels, combined with a bolt passing through both 55 wheels and the hollow of the pins; the crank case being arranged to supplement said bolt in preventing the fly wheels from spreading.

6. The combination, in an internal combustion engine, of a cylinder and crank case constituting a mixing chamber adapted to 60 receive and enclose a preparatory mixture of fuel and air; a crank in said case and a fly wheel attached thereto and nicely fitting within the crank case with its perimeter in 65 close proximity to the open end of the cylinder; said perimeter being circular except that on the side of the axis which is toward the crank pin the circle is broken for a distance approximating the cylinder diameter, whereby the said chamber undergoes 70 continuous change of shape as the noncircular portion of perimeter moves past the open end of the cylinder, while the chamber volume is changing relatively slowly.

Signed at Boston, Massachusetts, this 15th 75 day of November, 1919.

GEORGE H. NOBBS.
